(Model.)

W. COKAYNE.
FENCE.

No. 320,223.

Patented June 16, 1885.

UNITED STATES PATENT OFFICE.

WILLIAM COKAYNE, OF GEETINGSVILLE, INDIANA.

FENCE.

SPECIFICATION forming part of Letters Patent No. 320,223, dated June 16, 1885.

Application filed July 2, 1884. (Model.)

To all whom it may concern:

Be it known that I, WILLIAM COKAYNE, of Geetingsville, county of Clinton, and State of Indiana, have invented a new and Improved 5 Fence, of which the following is a full, clear, and exact description.

The object of my invention is to provide a new and improved fence which is simple in construction, strong and durable, and can be 10 erected easily and rapidly.

The invention consists of the combination of parts and their construction, substantially as hereinafter fully set forth and claimed.

Reference is to be had to the accompanying 15 drawings, forming a part of this specification, in which similar letters of reference indicate corresponding parts in all the figures.

Figure 1 is a longitudinal elevation of two 20 panels of my improved fence. Fig. 2 is a sectional plan view of one of the panels. Fig. 3 is a sectional elevation of the fence. Fig. 4 is a detail sectional plan view showing the manner 25 of bracing the posts.

The fence rests on transverse bed-pieces or 30 sills A, each provided at the middle with two apertures separated a distance about equal to the thickness of the rails B, in which apertures the lower pointed ends of stakes or posts C are driven, of which the one on the outside 35 of the fence is higher than the one on the inside, the inner post being about flush with the uppermost rail. The stakes or posts C are braced by means of a wire, D, one end of which is secured on a nail, E, or a stud or like device, driven into one side edge of the base. Then the wire is carried up and secured on a nail, E', projecting from one side edge of one 40 standard C about one-third of its height from the bottom, the said nail E' being on that side edge of the post opposite the one on which the nail E projects from the base. Then the wire is carried diagonally across the space between the two posts or stakes and secured on a nail, E', projecting from one side edge of the other 45 post, and is then carried down to the opposite end of the base, and is secured to a nail, E. The two nails E on the opposite ends of the base project from opposite side edges of

the base, and the two nails E' on the stakes project from opposite side edges of the same, 50 so that the wire will extend transversely across the base from one end to the middle, then in the opposite direction across the space between the two stakes, and then diagonally across the base from the middle of the same to the opposite free end, as is shown in Figs. 2 and 4. That part of the wire that crosses the space between the two stakes diagonally is below one 55 of the rails B. The rails B are placed between the stakes, the ends of the rails overlapping, 6c so that the rails will be inclined a distance about equal to the height or thickness of the rail. Above the uppermost rail the opposite stakes C are tied together by means of a wire loop, G, or a band. A wire, H, which may 65 be plain or barbed, may be secured to the upper ends of the higher posts, if desired. The end panels of the fence are braced by means of slats or strips J, having their upper ends nailed to the inner surfaces of the high posts C, and 70 then extending across the rails B on the outside of the fence, the said brace-strips J being nailed to the several rails. The lower ends of the braces J rest on the edges of the bases A, as shown. If desired, some of the intermediate 75 panels can also be braced.

The fence requires no post-holes, as the bases rest on the ground.

Having thus described my invention, I claim as new and desire to secure by Letters Patent— 80

The combination of the stakes inserted into bases and looped or connected together, the rails, the oblique board braces and the wire braces, each being a continuous wire fastened at one end to one side of a base, thence extended up and connected to the opposite side of a stake and passed to the opposite side of the fellow stake and fastened, and thence carried down and fastened to the opposite side of said base, substantially as and for the purpose 90 set forth.

WILLIAM COKAYNE.
